GABRIEL BECKER, OF BERLIN-CHARLOTTENBURG, GERMANY

STARTING DEVICE FOR INTERNAL COMBUSTION ENGINES

Application filed January 5, 1932, Serial No. 584,849, and in Germany November 30, 1931.

This invention relates to starting devices for internal combustion engines of the kind wherein a distributor feeds a gaseous pressure fluid to the engine cylinders in the appropriate working order and has for its principal object the provision of means operable in timed relation with the engine for automatically interrupting the feeding of fluid by the distributor at the expiration of 10 a predetermined period.

To achieve this, use is made of a cam plate axially slidable on its driving shaft and effective in the direction of said driving shaft, and a plurality of valves arranged 15 concentrically around and parallel to the shaft and opened and closed positively by the cam-plate, and control mechanism which automatically and positively controls the shifting of the cam plate into the operative and inoperative positions. Preferably this 20 control mechanism, after a certain number of revolutions of the engine, releases the cam plate, which is held in its operative position during the starting operation, so that it can 25 be moved axially into its inoperative position out of reach of the valves. Conveniently this release is effected through the agency 30 of a nut traversing a threaded spindle. The released cam-plate will move back by spring- 35 force into its inoperative position. By this means the operative connection between the cam-plate and control valves is discontinued and the control valves, acting automatically 40 and independently of the pressure of the pressure fluid, cut off the further supply of the fluid. At the same time the nut, with the aid of a stop, also arrests the control mechanism. For re-starting, the cam-plate 45 is returned to the operative position by manually winding back the nut into the position in which it holds the cam-plate, so that, by the re-establishment of the operative connection between the cam-plate and valves, the starting operation is initiated directly and 50 without the opening of a separate cut-off cock.

Details of the invention are described below with reference to the drawing wherein like parts are indicated with the same reference numeral in the different figures:—

Figure 1 is a side elevation of an internal combustion engine with a starting device built on to it. 60

Figure 2 is a longitudinal section through the starting device, the cam-plate being in its operative position and the nut in its extreme position at the commencement of the starting operation. 55

Figure 3 is the same longitudinal section as Figure 2 but shows the fully inoperative condition of the device, the nut being in its other extreme position and the cam plate in its inoperative position whilst the drive for the control mechanism is also disengaged. The hand-crank for re-starting is 60 also illustrated in this figure. 65

The internal combustion engine 1 may be of any desired construction. The flanged housing 3 of the starting device is conveniently secured co-axially with the engine cam-shaft 2. The pressure fluid is contained 70 in a vessel 4 and fills the pressure chamber 6 of the distributor 7 through a tube 5.

Normally, the pressure fluid is cut off by the valves 8, there being a number of these corresponding to the number of cylinders. 75 When the distributor is set in operation, the pressure fluid flows, under the control of the valves 8, through the starting tubes 9 to the individual cylinders. The cam plate 10, which is then in its operative position as 80 shown in Figure 2, is driven from the engine cam-shaft 2 (Figure 1), through the shaft 11, by the feather or key 37 and is axially slid able on the shaft 11 in the direction of lift of the valves 8 which are arranged on a concentric circle around the shaft 11 so that they open and close in the axial direction of 85 said shaft.

Through gear wheels 12, 13 and a clutch 14, the shaft 11 also drives a threaded spin- 90

dle 16 which is secured against axial movement by collars 15 and on which a nut 17 is traversed. The clutch 14 is only effective in the driving direction of rotation and serves 5 as a non-return device for protecting the nut 17 when it abuts against the collar 22. The end portions of the movements of the nut on the spindle 16 are transmitted through rods 18, 19, connected by a lever 20, to a toggle 10 linkage 21. Figure 2 shows the nut 17 in position against the shaft-collar 22 at the commencement of the starting operation. It is holding the toggle linkage 21 in its locked 15 position by means of a stop 23 on the rod 18. In turn the toggle linkage holds the cam-plate 10 in its operative position by means of collars on a pin 24. To retain the toggle linkage in this position, the rod 18 is provided with a spring 26 acting upon a stop 25.

20 During the starting operation the nut 17 travels along the threaded spindle 16 towards the extreme position illustrated in Figure 3. It thus encounters the stop 25 and, through the linkage 18, 19, 20, draws the 25 toggle linkage 21 out of its locked position, so that the cam-plate 10 returns to its inoperative position against the collar 29 under the pressure of the spring 27 assisted by the closing-springs 28 on the valves 8. In 30 this manner, all the valves 8 are closed by their springs 28 and the pressure fluid is cut off.

The nut 17 on encountering the stop 25 also moves, through a stop 30, an arm 31 whereby the gearwheel 13, which is axially 35 displaceable, is brought out of engagement with the driving wheel 12. The spindle 16, together with the nut 17, comes to a standstill. The spring 27, which becomes operative at 40 the same time and moves the cam-plate back 45 into the inoperative position in the manner described, assists in pressing, through the toggle linkage 21 and stop 30, against the arm 31 so that the proper disengagement of the toothed wheel 13 is ensured.

50 The return of the cam-plate 10 into the operative position shown in Figure 2 is effected by turning the spindle 16 backwards by means of a crank handle 32 having a crown- 55 wheel 33 which, on the insertion of the handle in the bore 34, engages with a toothed wheel 35 on the shaft 16. By this means the nut 17 is returned from the position of Figure 3 towards the stop 23, whereby it presses 60 the toggle linkage 21 into its locked position, as shown in Figure 2. The collar 22 restricts the return movement of the nut 17.

65 The insertion of the handle 32 temporarily prevents engagement of the toothed wheel 13 with the driving wheel 12. Upon withdrawal of the handle 32, the spring 36 is effective for moving the wheel 13 into such engagement.

65 The control mechanism described represents only one of the various arrangements

possible for the automatic displacement of the cam plate. What is of primary importance for the invention is that after a pre-determined number of revolutions, or at a predetermined revolution speed, of the engine, the driving means for the distributor is automatically disengaged. It should, therefore, be expressly observed that the invention is not to be regarded as restricted to this constructional form selected for the purpose of furnishing the clearest possible explanation.

I claim:—

1. Starting device comprising means for distributing gaseous pressure fluid to the cylinders of an internal combustion engine, said distributing means consisting of a plurality of valves, a driving shaft, a cam plate rotatable by said shaft engageable with said valves for actuating the same in succession, self-locking means for maintaining said cam plate in an operative position for actuating said valves, means for displacing said cam-plate axially on the shaft to an inoperative position, and a release device actuated from the driving shaft for releasing the self locking means to permit of the displacement of the cam plate to the inoperative position.

2. Starting device according to claim 1, wherein the release device comprises a threaded spindle, means for driving said spindle from the shaft, a traversing-nut on said spindle, stop devices engageable by said nut in its traversing movement and an operative connection between said stops and the self-locking means, said self locking means being moved into and out of the locking position under the control of the nut.

3. Fluid pressure starting device for internal combustion engines, comprising a plurality of fluid-distributing valves, a cam for actuating said valves, a driving shaft upon which said cam is axially shiftable into and out of engagement with said valves, mechanism for so shifting said cam, a threaded spindle, a disengageable driving gear between said spindle and shaft, a traversing nut on the spindle, said nut being engageable with said mechanism for controlling the axial shifting of the cam, and a gear shifting device controlled by the nut for effecting the engagement and disengagement of the driving gear at the same time as that of the cam.

4. Starting device according to claim 3, a one-way clutch device being provided between the driving gear and the threaded spindle for the purpose set forth.

5. Fluid pressure starting device for an internal combustion engine comprising a plurality of fluid-distributing valves, a cam for operating said valves in succession, a driving shaft upon which said cam is axially shiftable into and out of operative engagement with the valves, mechanism for axially shifting said cam on said shaft and

means including a time-lag device driven by said shaft and operatively connected with said cam-shifting mechanism to effect disengagement of the cam from the valves.

- 5 6. Starting device according to claim 5, wherein a disengageable driving connection is provided between the shaft and time-lag device, and means operable by the cam-shifting mechanism for disengaging said driving
10 connection when said mechanism is operated to disengage the cam from the valves.
